UNITED STATES PATENT OFFICE.

EMIL W. NEU, JOSEPH A. WEBER, AND HARRY E. KEYES, OF HOMESTEAD, PENNSYLVANIA, ASSIGNORS TO HOMESTEAD HEATER AND MANUFACTURING COMPANY, OF HOMESTEAD, PENNSYLVANIA, A CORPORATION OF PENNSYLVANIA.

WATER-HEATING APPARATUS.

SPECIFICATION forming part of Letters Patent No. 783,457, dated February 28, 1905.

Application filed December 14, 1903. Serial No. 185,102.

To all whom it may concern:-

Be it known that we, EMIL W. NEU, JOSEPH A. WEBER, and HARRY E. KEYES, citizens of the United States, residing at Homestead, in the county of Allegheny and State of Pennsylvania, have invented new and useful Improvements in Water-Heating Apparatus, of which the following is a specification.

Our invention relates to apparatus for heating water for domestic purposes; and its main objects are to provide a simple, efficient, and compact apparatus having all of its parts readily accessible for cleaning, adjustment, and repairs and having such of its parts as require special care and attention so constructed and arranged as to be readily removable without disturbing other parts of the apparatus or without breaking any connections other than those directly associated with the particular parts to be removed.

To these ends our invention consists in the novel construction and arrangement of the various parts of the apparatus to be hereinafter described, the particular features of novelty being specified in the claims hereunto annexed.

Referring to the drawings furnished and forming a part of this specification, Figures 1 and 2 represent in side and front views, respectively, an apparatus embodying our invention. Fig. 3 is an enlarged side view of the water-heating apparatus and the lower part of the water tank or reservoir. Fig. 4 is a front view of said heating apparatus with the front wall of the casing or cover removed for disclosing the water-heating coil and the heating-burner. Fig. 5 is a plan or top view of the burner. Fig. 6 is a plan or top view of the heater, and Fig. 7 is a sectional view of the casing inclosing the fuel-valve and its thermostatic controlling device.

The water reservoir or tank A may be of any suitable size, shape, and construction and is provided with a water-inlet pipe a and an outlet-pipe a' , through which water passes from said tank to the heating apparatus, said outlet-pipe being preferably connected to the

bottom of said tank, as shown, in order that said tank and the thermostatic device to be hereinafter described may be readily cleaned, as will be hereinafter explained.

The pipe a' leads to a heating-coil B, which in turn is connected to a pipe a'' , leading to the top or upper end of the tank or reservoir A, and connected to said pipe a'' is a pipe a^3 , from which the heated water is drawn for service. The construction and arrangement of the tank or reservoir and its connecting-pipe is as heretofore constructed and forms no part of our present invention. The water-heating coil B is in plan view in the form of the figure 8, this particular shape being for the purpose of securing a large area of heating-surface in a comparatively small space and for the further purpose of having the coil so shaped that it will lie close to the cylindrical wall of the water tank or reservoir and occupy as little space as possible outside of the space occupied by the tank itself. Said coil is wholly supported by the pipes to which it is connected. The pipe a' is directly connected to a valve-casing D, the latter serving as an elbow connection between the pipe a' and the lower end b of the heating-coil B, the latter being detachably connected to said valve-casing by means of a coupling-nut b^2 in a well-known manner. The upper end b^3 of said coil is connected in a similar manner to the pipe a^3 by means of a coupling-nut b^4 .

Surrounding the coil B is a casing C, which is attached to and supported by the water tank or reservoir A. Said casing, which is preferably composed of cast metal, is made to closely conform to the shape of the heating-coil and comprises a fixed upright wall c , an integral top wall c' , and a removable upright wall c^2 . The fixed wall c incloses the rear half of the heating-coil, and the removable wall c^2 incloses the front half of said coil, said removable wall being secured in place by means of thumbscrews c^3 , which project from its side edges and enter slots c^4 in the side edges of the fixed wall c , all of which will be readily understood.

from the drawings without further explanation, it being only necessary to call attention to the fact that when the casing-wall c^2 is removed, as shown in Fig. 4, the heating-coil B 5 and the burner E are sufficiently exposed for an ordinary cleaning operation. The fixed portion of the casing C is secured to the water-tank A by means of a band c^5 , which extends around said tank and has its ends secured to 10 said casing, as clearly shown.

The burner E, which is located directly beneath the heating-coil B, is a hollow cast-iron structure of sufficient capacity to serve as an air and gas mixer. It is provided with an air 15 and gas inlet e , and on its top there is a series of perforations e' , through which the combined air and gas escapes to form the heating-jets. The shape of the burner is best shown in Fig. 5, its general appearance being that 20 of two rings connected together at one side of a central line, the central space e^2 being provided for the lower end of the heating-coil B. Said burner is supported at its ends by the fixed wall c of the casing C, the latter being provided with open slots e^3 for the reception of 25 screws e^4 , tapped into bosses e^5 at the ends of the burner. The bottom of the casing C being open, the burner E is pushed up into the casing, so that the screws e^4 will enter the slots e^3 , the 30 burner being held in place by tightening the screws, as will be readily understood. This mode of supporting the burner not only admits of it being readily removed for cleaning purposes, but also admits of an adjustment of 35 the burner to a truly horizontal position, this adjustment being an important feature in an apparatus of this character for the reason that should the burner be higher at one end than at the other the gas will seek the elevated 40 end of the burner and leave little or none for the depressed end, and thus cause an uneven heating of the coil. By supporting the burner so that it may be tilted as described no particular care is necessary in setting up the apparatus 45 in order that the burner may operate to the best advantage.

Connected to the burner-inlet e is a short length of pipe e^6 , and at the lower end of said pipe there is a cone e^7 , which surrounds the 50 gas-supply nozzle f , so that air may enter the burner through the space between the lower end of said cone and said nozzle f , as will be readily understood. The cone e^7 is secured to the pipe e^6 by means of a set-screw e^8 , the latter being loosened to enable the cone to be raised 55 when the burner E is to be removed from the apparatus.

The gas-supply or service pipe F is connected to the valve-casing D and is provided 60 with a cock f' for controlling the maximum supply of gas to the burner. The valve-casing D is provided with an entrance-chamber g and an exit-chamber g' , the division-wall g^2 , separating the two chambers, being provided 65 with a port g^3 , controlled by a valve G, which

is moved for opening and closing the two chambers by a thermostatic device to be presently explained. The valve G is conical in form and is made to closely fit a conical seat in the partition-wall g^2 and is provided with 70 a by-pass g^4 for the passage of a small quantity of gas to the burner, so that the latter may not be entirely extinguished by the closing of said valve. The quantity of gas which is permitted to pass through the by-pass g^4 is 75 controlled by a thumb-screw g^5 , arranged opposite said by-pass to regulate the opening in a well-known manner. Gas from the supply or service pipe F enters the valve-chamber g and passes therefrom to the chamber g' and 80 thence to and through the discharge-nozzle f to the burner E.

The valve G is mounted upon the end h of a rod H, said end h being screw-threaded, so that the valve may be accurately adjusted with 85 respect to the movements of the rod H, the latter forming a part of the thermostatic device hereinbefore referred to. Said rod H extends back through the valve-casing into the pipe a' , leading from the water-tank to the 90 heating-coil B, and is surrounded by a tube H^2 , composed of metal or alloy having a comparatively high coefficient of expansion. Said tube is fixedly secured to the rear end of the rod H, preferably by means of an internally 95 and externally screw-threaded nut or collar h' , as will be readily understood. The forward end of said tube is secured to the valve-casing by means of an externally-threaded hub h^2 , to which said tube is fixedly attached. The rear wall of the valve-chamber g' is provided with a screw-threaded opening h^3 to receive the hub h^2 , and at the rear of said opening there is an annular flange or abutment h^4 , between which and the rear end of 100 said hub is placed a lead washer h^5 in order that a perfectly tight joint may be secured between the chamber g' and the rear of the valve-casing.

The valve G and the thermostatic device 105 are adjusted, removed, and inserted through the front end of the valve-casing, the latter being provided with a removable cap or cover D'. When this cap or cover is removed, the supply of gas through the by-pass g^4 may be 110 adjusted by turning the screw g^5 . The valve itself may be adjusted by simply turning or rotating it so that it will be advanced or withdrawn from its seat by means of its screw-threaded connection with the rod H. The valve 115 may be removed from the casing or the thermostatic device may be withdrawn from the valve-casing for cleaning or repairs by turning or unscrewing the hub h^2 , the latter being provided with a square projection h^6 for the 120 purpose.

The valve G, the thermostatic device, the burner E, and the heating-coil B require constant care and attention in order that the best possible results may be attained at the small- 125 130

est possible cost. The burner must of course be kept open and as free as possible from deposits from the gas and products of combustion, and for this purpose it is readily accessible by removing the front wall of the casing C, or may be readily removed, as already explained, without disturbing any other part of the apparatus. The coil B must also be frequently cleaned, as the deposits which rapidly accumulate thereon tend to prevent the heat from reaching the water in the coil, and it frequently happens that such deposits become so thick and hard that it is necessary to remove the coil from the apparatus in order that it may be thoroughly cleaned. When the front wall of the casing C is removed, as already explained, the coil is exposed sufficiently to permit it to be cleaned, provided the deposit thereon is not so thick and hard as to render the operation difficult. When necessary, the coil B may be readily removed (after the burner has been removed) by unscrewing the coupling-nuts b^2 and b^3 . The upper end of the coil may then be lowered through the perforation c^5 in the upper wall of the casing C and removed from said casing, as will be readily understood.

In the operation of the apparatus the water in the tank A circulates through the coil B by way of the pipes a^1 and a^2 , the water as it becomes heated in the coil ascending through the pipe a^2 and the cooler water at the bottom of said tank passing to the coil by way of the pipe a^1 . As the temperature of the water increases it causes the tube H^2 of the thermostatic device to expand and move the rod H rearwardly for gradually closing the valve G, the latter being entirely closed when the water reaches the desired temperature. The gas supplied to the burner is thus automatically controlled and regulated by the temperature of the water in the tank or reservoir A. Said burner, as heretofore explained, is always supplied with a small quantity of gas and is consequently not extinguished by the closing of the valve G; but the flame of the burner is increased or decreased as the temperature of the water may require.

The thermostatic tube H^2 must be kept as clean as possible, so that it may quickly respond to changes in the temperature of the water, and for this purpose the valve-casing D is provided with a water-discharge outlet z , which is controlled by a cock or faucet I. This water-outlet is for the purpose of drawing the water from the tank A through the pipe a^1 , so that the water in its passage through said pipe will act to cleanse the tube H. The latter may, however, when a more thorough cleaning is necessary be removed from the valve-casing, as before explained.

Having thus described our invention, what we claim as new, and desire to secure by Letters Patent, is—

65 1. In a water-heating apparatus, the combi-

nation with a water tank or reservoir, of a heating-coil, an independently-supported casing surrounding said coil, pipes connected to said reservoir for conveying water to and from said coil, the latter being detachably connected to 70 said pipes and wholly supported thereby, the organization being such that said coil may be removed from said casing after being detached from the pipes to which it is connected, substantially as described.

2. In a water-heating apparatus, the combination with a water tank or reservoir, of a heating-coil, pipes connected to said reservoir for conveying water to and from said coil, the latter being detachably connected to said pipes 80 and wholly supported thereby, and a casing for said coils secured to and supported by said tank or reservoir, said casing having a removable wall for giving access to said coil, substantially as described.

3. In a water-heating apparatus, the combination with a water tank or reservoir, of a heating-coil, pipes connected to said reservoir for conveying water to and from said coil, said coil being detachably connected to said pipes 90 and wholly supported thereby, a casing surrounding said coil, and a burner detachably secured to and supported within said casing below said coil, the organization being such that said coil and burner may be readily removed 95 from said casing, substantially as described.

4. In a water-heating apparatus, the combination of a water-heating coil, a casing for said coil open at its lower end, slots in the side walls of said casing at the lower edge 100 thereof, a burner provided with projections at opposite edges adapted to enter said slots, and means for adjustably securing said projections in said slots, substantially as described.

5. In a water-heating apparatus, a heating- 105 coil having each of its convolutions in the form of the figure 8, a casing for said coil, and a burner located beneath said coil, said burner being shaped to conform to the shape of said coil, substantially as described.

6. In a water-heating apparatus, a heating-coil having each of its convolutions in the form of the figure 8, a casing surrounding said coil, a burner located beneath said coil, said burner being shaped to conform to the shape of said 115 coil and being supported at its ends by said casing, substantially as described.

7. In a water-heating apparatus, the combination with a water-heating coil having suitable inlet and outlet connections, of a burner, a valve for controlling the fuel to said burner, a valve-casing for said valve having a removable cap or cover for giving access to the interior thereof, a thermostatic device detachably supported in said casing and adapted to 120 be readily removed therefrom, said device projecting into the inlet connection leading to said coil and being adapted to control the movements of said valve, substantially as described.

8. In a water-heating apparatus, the combination with a water tank or reservoir, of a heating-coil, inlet and outlet connections for said coil leading to and from said reservoir, a burner located beneath said coil, a valve for controlling the supply of fuel to said burner, said valve being inclosed in a suitable valve-casing, a thermostatic device located in the coil-inlet connection adapted to control the movements of said valve, and a water-discharge outlet located in the wall surrounding said thermostatic device, substantially as and for the purpose set forth.
9. In a water-heating apparatus, the combination with a water-heating coil, of a burner located beneath said coil having suitable water inlet and outlet connections, a valve for controlling the supply of fuel to said burner, said valve being inclosed in a suitable valve-casing, a thermostatic device supported in said valve-casing and projecting into the inlet connection leading to said coil, and a by-pass through said valve for permitting a small quantity of fuel to pass to said burner when said valve is closed, substantially as and for the purpose set forth.
10. In a water-heating apparatus, the combination with a water-heating coil having suitable inlet and outlet connections, of a burner located beneath said coil, a valve for controlling the supply of fuel to said burner, said valve being inclosed in a suitable valve-casing, a thermostatic device for automatically controlling the movements of said valve, said device being supported in said valve-casing and projecting into the inlet leading to said coil, a water-discharge outlet in the wall of said valve-casing adjacent to said thermostatic device, and a valve or cock for controlling said water-discharge outlet, substantially as described.

In testimony whereof we have hereunto set our hands in presence of two subscribing witnesses.
